UNITED STATES PATENT OFFICE.

FREDERICK L. ODENBACH, OF CLEVELAND, OHIO, ASSIGNOR OF ONE-HALF TO JOHN C. POORE, OF CLEVELAND, OHIO.

RAILWAY SIGNAL AND TELEPHONE SYSTEM.

No. 885,367.

Specification of Letters Patent.

Patented April 21, 1908.

Application filed July 10, 1907. Serial No. 383,080.

To all whom it may concern:

Be it known that I, FREDERICK L. ODENBACH, a citizen of the United States, residing at Cleveland, in the county of Cuyahoga and

5 State of Ohio, have invented certain new and useful Improvements in Railway Signal and Telephone Systems, of which the following is a specification.

This invention relates to means for signaling and telephoning moving train units and stationary points upon railways. Its primary object is to give certain signals automatically within the operator's cab of a locomotive or railway motor of any kind, at rail- 15 way crossings, and at terminal stations.

It also provides a telephone system between moving train units, and between moving and stationary points, and between stationary points upon railways. It is intended 20 to accomplish such signaling and telephoning only within certain predetermined limits.

Further objects are, to provide means upon moving railway units enabling the operator of each unit to determine whether the other 25 is behind or before him, and at what speed such other unit is moving; to apprise the operator of a moving car or train of an open switch, or signal of danger ahead of him; and to adapt said means to a block system, or lo- 30 cal system, wherever such system is desired.

Minor objects and applications of the invention will become apparent from the following description.

To these ends my invention consists in the 35 features, arrangements and combinations of the electrical and mechanical apparatus hereinafter described and claimed, embodiments thereof being illustrated diagrammatically in the accompanying drawings wherein

40 Figure I is a diagram showing the system as applied to two movable train units headed toward each other upon the same railway track. Fig. II illustrates a galvanometer, or distance indicator, such as is employed 45 upon the movable train units. Fig. III is a perspective view of one side, and Fig. IV is a similar view of the other side of the automatic revolving switch employed upon locomotives or movable train units. Fig. V is a diagram 50 illustrating the system as installed in a movable train unit, a railway switch, and a crossing tower or terminal station.

The reference letter *a* indicates the track 55 rails of a railway which should be continuously connected to form a perfect electrical

ground or return conductor. A trolley wire *b*, or other continuous electrical conductor, is stretched above or alongside the track *a* and insulated from the ground.

In Fig. I, the diagram at *c* represents the apparatus upon a locomotive or car, and the diagram at *d* is the apparatus upon another locomotive or car, the two movable units *c* and *d* being headed toward each other upon the same track *a*. Each engine or car is provided with a trolley pole *e* having the usual, or any suitable equipment for making electrical connection with the conductor *b*, and it is preferably secured to the cab of the locomotive as shown in Fig. V. A source of 60 electricity *f* is carried upon each movable train unit, which may be a battery or other generator, but a small dynamo is preferred. Within the operator's cab of the locomotive or car I provide a three way switch *k*, an automatic rotatable switch *j*, a commutator *h*, a galvanometer *g*, a switch *m*, a lamp *l*, and a telephone *n*, which with their connections 65 will now proceed to describe.

The rotatable switch *j*, as shown in Figs. 70 III and IV, comprises a cylinder of insulating material having an axial shaft 2, which should be rotatably mounted in suitable bearings and operatively connected with a track wheel axle of the engine or car so as to 75 be revolved by the latter. The operative gearing between the axle and the switch *j* should be the same in each train unit, and arranged to revolve the said switch about once per second of time at the ordinary road 80 speed of the car or train. A metallic band 3 encircles the periphery of the cylinder *j*, and upon each side of it are similar bands 4 and 5, electrically connected therewith, but the latter bands encircle only one half of the cylinder, the band 4 being upon one side and the band 5 upon the opposite side of said cylinder, as plainly shown. A metallic brush, or contactor, 6 is set to ride upon the central band 3, a similar contactor 7 rides upon the band 4, and another similar contactor 8 rides upon the band 5, as shown in Fig. I. Thus it is obvious that the brush 6 is always in contact with the metallic portion of the switch *j*, while the brushes 7 and 8 are alternately in and out of contact with the metallic part of said switch.

Normally the switch *k* is thrown to the center, as shown, so that the generator *f* and ground *a* alternate. The three way switch *k* 110

may also electrically connect the trolley *e* with either the brush 7 or the brush 8 according as it is thrown to the one or to the other. A wire 9 leads from the brush 7 to 5 one of the upper posts of the commutator, or reversing switch, *h*, and a wire 10 connects the brush 8 with the other upper post of said commutator. The lower posts of the commutator *h* are connected respectively through 10 the wires 11 and 12 with the respective poles of the electrical generator *f*, as shown. A wire 13 connects the wire 10 with one joint of the double pole, double throw switch *m*, and a wire 14 connects the other joint of said 15 switch with the ground, or return circuit which is made through the wheels of the movable train unit and through the rails of the track.

From one pole of one side of the switch *m* 20 a wire 15 leads to an incandescent electric lamp *l*, and a wire 16 connects said lamp with the other pole of the same side of the switch *m*, as shown. The poles of the other side of the switch *m* are connected respectively through the wires 17 and 18 with the 25 telephone *n* in the usual and well known way for operating telephones. Thus it will be seen, that when the switch *m* is in the position shown the lamp *l* will glow while electric current is passing along the wires 13 and 14, but when the said switch is thrown to the 30 position shown by the dotted lines the said lamp will be cut out, and the telephone *n* may be operated by the current passing along 35 said wires.

I insert in the wire 13 a galvanometer, or direction indicator, *g*. This may be of the type illustrated in Fig. II, having a pointer 19 pivoted at 20, and movable over a graduated scale 21. The said scale has its zero point in the middle, and may be marked "East" at one end and "West" at the other, or the ends may be marked respectively "North" and "South", or "In" and "Out", 40 or any way that may be preferred to indicate the direction of an approaching train. The pointer 19 has magnets 22 and 23 projecting each way from it into the respective helices 24 and 25 of the wire 13, so that the 45 said pointer will be moved to the right or to the left according to the direction of the electric current following the wire 13.

In Fig. V, *c* represents a locomotive, or train unit, equipped as in diagram *c* of Fig. I. 50 A track switch is indicated at *o*, which is provided with an electrical make and break switch as shown diagrammatically at *p*. A wire 26 leads from the line conductor *b* to one end of the switch *p*, and a wire 27 leads from 55 the other end of said switch to the track rail *a*. The electric switch *p* should be set to close when the track switch *o* is opened to a side track, and to open when the track switch is closed to make the main track continuous.

60 65 A railway crossing is indicated at *r*, Fig.

V, and *s* is a crossing tower. *s* also indicates the equipment of a terminal station, as will be hereinafter further described. The line conductor *b* is carried into the crossing tower, or terminal station, and connected to 70 one joint of a double throw, double pole switch *m* similar to the switch *m* upon a locomotive. From the other joint of the switch *m* a wire 28 leads to the ground at the rail *a*, having a make and break switch *q* therein. An electric lamp *l* is connected to the poles of one side of the switch *m*, and a telephone *n* is connected to the poles of the other side of the said switch, as shown, in the same way as upon a locomotive. In crossing towers 80 the line conductor *b* for each railway track is led therein and through the switch *m* and the switch *q* to the ground at *a*. For crossings of single track railroads the line conductors *b* from each direction of each track should be 85 led into the tower, and provided respectively with switches *m* and *q*, lamp and telephone connections, and with ground connections. The conductor *b* from each direction of on-coming trains should have its respective 90 lamp *l*, but a single telephone *n* may be connected, as shown, so as to be switched into any one of the lines *b* entering the tower. At a terminal station the equipment is substantially the same as for one line *b* entering a 95 crossing tower.

Bearing in mind that the fundamental idea of the system is found in the fact that two train units, or one train unit and a short circuit will constitute a block and give a danger 100 signal, the operation of the system in its various applications may be readily traced and understood. The length of the block, or distance over which signals are given, can be determined by the amount of electric current sent out by the generators *f* as related to the amount of resistance in the line conductor *b*. Therefore, two trains placed upon the same track within the said dangerous 105 distance fixed as described will automatically signal one to the other. Open switches will give a signal upon a train within the said distance. A train approaching within the said distance of a crossing or terminal will signal the crossing tower or terminal station, 110 as the case may be; and said tower or station attendant may stop said train by a signal in the engine cab thereof. All the parties mentioned may telephone each other. And the operators of trains are apprised of the approximate 115 location, speed and direction of movement of other trains entering within the aforesaid fixed distance.

Referring to Fig. I, let us consider *c* a train coming in, and *d* a train going out. The commutator *h* and switch *k* of the respective trains are normally set as shown; so that current from generator *f* of train *d* would, when the two trains approached close enough to 120 make a circuit, pass along wire 12, commu- 130

tator *h*, wire 9, brush 7, revolving switch *j*, brush 6, switch *k*, and trolley *e* to line conductor *b*; said current being interrupted during alternate half revolutions of the rotatable switch *j* when the brush 7 is riding upon the insulated portion of said switch. During the said interruptions the brush 8 rides upon the metallic part of the rotatable switch *j*, which will complete a circuit from the approaching train *c* through rail *a*, wire 14, lamp *l*, indicator *g*, wires 13 and 10, brush 8, switch *j*, brush 6, switch *k*, and trolley *e* to the conductor *b*. Substantially the same effect occurs upon the train *c*, but the direction of current is reversed, because of the different position of the commutator *h* upon the latter train. Thus, the lamps *l* glow upon both trains, giving notice that another train has entered the fixed limit of distance. A normal flash of said lamp alternating with a much stronger flash, or an almost constant light, shows a train ahead. The galvanometer *g* will also show this by moving to the side corresponding to the line ahead, and by indicating the increase of current through the reduction of line resistance, it will show the approximate speed of the approaching train, as will also the rapidity of the flashes given by the lamp when the operator throws out the local generator *f* and permanently completes the circuit for the other train by throwing the switch *k* to the head of the brush 8. By throwing the switches *k* to 7, and throwing over the switches *m*, it will readily be seen that any two trains on the same track within a limited distance may telephone each other. A train may also telephone a crossing tower or terminal station in the same way, when the attendant at has thrown over his switch *m* and closed his switch *q*.

If upon a train there is a normal flash of the lamp *l* intermitting with a weak one, there is another train in the rear. The indicator *g* will also show the direction of the other train. Then by throwing the commutator *h* so as to join the local generator *f* with the generator in the rear train, an increased flash of lamp *l* alternating with a normal flash, and the indicator *g* still pointing in the same direction, will confirm the first signal.

If a regular single flash only is observed, with no other lamp effect, it indicates that a stationary short circuit has been made with the train. This may be made by an open switch *o*, or by a crossing tower or terminal *s*, or by any temporary danger signal which may be made anywhere along the road by electrically connecting the line conductor *b* with the track *a*. This signal may also be made by a standing train, which latter, when it comes to a stop, should throw out its generator *f* and ground its trolley *e* by throwing its switch *k* to 8.

The revolving switch *j*, as will be under-

stood from the diagrams, alternately sends out the local current, and runs to ground to take up a signal from an outside source. The lamp *l* and galvanometer *g*, it will be noticed, are not cut out in grounding the trolley pole 70 *e*. It will also be noticed that the two generators *f* on locomotives in danger of a head-on collision run out in such a way as to form one; but that two locomotives following each other will naturally set theirs against 75 each other, and if they are equally strong no lamp flash would result; but, since each generator is cut out and in automatically, and since there is no danger of their synchronizing, there is always a chance for each to do 80 its work during part of each revolution of the rotatable switch *j*.

The ends of the line conductor *b* may be either open or closed. If open the in-coming train will get no signal. But if the end 85 of *b* is grounded the in-coming train will get a signal as soon as it has reduced the resistance of the line *b* enough to operate its lamp *l*. At crossing towers, and at terminal stations when desired, the switches *q* should be 90 closed to ground the conductor *b*, so that the guard may know of an approaching train. The guard may then telephone the train, or by opening the switch *q* may stop the said train, for in the latter case the lamp on the 95 train has ceased to glow upon the opening of the switch *q*.

The system is adapted for mere local use on curves, in tunnels, or at other dangerous stretches of track where any line conductor 100 *b* may be set up and any suitable contact former *e* employed. And the nature of the system will suggest other serviceable applications.

I further point out and distinctly claim as 105 my invention—

1. In a railway signal system, the combination with a track rail, a line conductor, and a train unit provided with an electric generator, of a rotatable switch upon said 110 train unit adapted to alternate the connection of said line conductor between said generator and said track rail, and an electric signal device connected between said track rail and said generator, substantially as set 115 forth.

2. In a railway signal system, the combination with a track rail, a line conductor, and a train unit provided with an electric generator, of a rotatable switch upon said train 120 unit adapted to alternate the connection of said line conductor between said generator and said track rail, a commutator connected between said generator and said switch, and an electric signal device connected between 125 said track rail and a switch connection of said commutator, substantially as set forth.

3. In a railway signal system, the combination with a track rail, a line conductor, and a train unit provided with an electric genera- 130

5 tor, of a rotatable switch upon said train unit adapted to alternate the connection of said line conductor between said generator and said track rail, a commutator connected between said generator and said switch, and an electric signal lamp in circuit between said track rail and said commutator and switch, substantially as set forth.

10 4. In a railway signal system, the combination with a track rail, a line conductor, and a train unit provided with an electric generator, of a rotatable switch upon said train unit adapted to alternate the connection of said line conductor between said generator and 15 said track rail, and an electric signal lamp in circuit between said track rail and said generator, substantially as set forth.

20 5. In a railway signal system, the combination with a track rail, a line conductor, and a train unit provided with an electric generator, of a rotatable switch upon said train unit adapted to alternate the connection of said line conductor between said generator and said track rail, and an electric signal 25 lamp and a galvanometer in circuit between said track rail and said generator, substantially as set forth.

30 6. In a railway signal system, the combination with a track rail, a line conductor, and a train unit provided with an electric generator, of a rotatable switch upon said train unit adapted to alternate the connection of said line conductor between said generator and said track rail, a commutator interposed 35 in the connections between said generator and said switch, and an electric signal lamp and a galvanometer in circuit between said track rail and a switch connection of said commutator, substantially as set forth.

40 7. In a railway signal system, the combination with a line conductor, and train units having electric generators adapted to be connected in circuit with said line conductor, of signal devices upon said train units adapted 45 to be connected intermittently and permanently in said line conductor circuit, substantially as set forth.

50 8. In a railway signal system, the combination with a line conductor, and train units having electric generators adapted to be connected in circuit with said line conductor, of signal devices upon said train units adapted to be connected intermittently and permanently in said line conductor circuit, and 55 telephones on said train units arranged to be connected in said circuit, substantially as set forth.

9. In a railway signal system, the combination with a line conductor, and an electric

60 generator upon a train unit adapted to be connected in circuit therewith, of a signal device upon said train unit provided with means for connecting it intermittently and permanently in said line conductor circuit, a 65 station provided with a signal device in circuit with said line conductor, and means in said station for opening and closing the said circuit, substantially as set forth.

70 10. In a railway signal system, the combination with a line conductor, and an electric generator upon a train unit adapted to be connected in circuit therewith, of a signal device upon said train unit, means for connecting said signal device intermittently and permanently in said line conductor circuit, a 75 track switch provided with an electrical connection in said line conductor circuit, and means for making and breaking said last named connection according to the position of said track switch, substantially as set 80 forth.

85 11. In a railway signal system, the combination with a line conductor, and an electric generator upon a train unit adapted to be connected in circuit therewith, of a signal device upon said train unit, means for connecting said signal device intermittently and permanently in said line conductor circuit, a station provided with a signal device in circuit with said line conductor, telephones in 90 both said station and said train unit arranged to be connected in said circuit, and means for opening and closing the said circuit, substantially as set forth.

95 12. In a railway signal system, the combination with a line conductor, and means for grounding the same to effect a danger signal, of a train unit comprising an electric generator, a signal device in circuit between said generator and the said ground, a three-way 100 switch, a connection from said switch to said line conductor, a power driven contactor adapted to alternate the connection of said line conductor between said generator and said ground, and connections whereby said three-way switch may be operated to ground said line conductor through said signal device or to throw said generator into the circuit between said line conductor and said signal device, substantially as set forth. 105

110 In testimony whereof I affix my signature in the presence of two subscribing witnesses at Cleveland, Ohio, this 6th day of July, 1907.
